CLAIM

The ornamental design for a sample testing tube kit, as shown and described.

DESCRIPTION

FIG. 1 is a rear perspective view of a sample testing tube kit showing my new design;

FIG. 2 is a left side elevational view thereof;

FIG. 3 is a right side elevational view thereof;

FIG. 4 is a top plan view thereof;

FIG. 5 is a rear elevational view thereof;

FIG. 6 is a distal end plan view thereof;

FIG. 7 is a front elevational view thereof;

FIG. 8 is a cross-sectional view thereof as taken along lines 8-8 in FIG. 6;

FIG. 9 is a cross-sectional view thereof as taken along lines 9-9 in FIG. 6; and,

FIG. 10 is an exploded perspective view thereof.

The broken lines depict portions of the sample testing tube kit that form no part of the claimed design.
